PISTON EXPANDER

David Bushby, Regina, Saskatchewan, Canada,
assignor to Vacuum Air Pressure Company Limited,
Regina, Saskatchewan, Canada, a company of
Saskatchewan, Canada

Application February 25, 1946, Serial No. 649,841
In Canada March 19, 1945

6 Claims. (Cl. 309—12)

1

This invention relates to a piston expander and is particularly directed to providing a frame for expanding a piston of the type used in the cylinder of an internal combustion engine.

One of the important objects of this invention is to provide an expander frame for pistons by means of which a worn piston skirt can be expanded easily, quickly, and accurately to bring all parts of the piston skirt into any desired tolerance fit with the cylinder wall.

A further important object of the invention is to provide an expander frame for pistons in which the expanding pressure is applied only to the piston skirt portion or portions necessary to bring all parts of the piston skirt into a desired tolerance fit within the cylinder wall.

A still further important object of the invention is to provide an expander frame for expanding pistons which may be easily installed and quickly adjusted either when the piston is installed in an engine cylinder or when detached therefrom.

A still further important object of the invention is to provide a piston skirt expander which is inexpensive to manufacture and which is easily installed.

The piston expander of the present invention comprises, in general, a frame having a resilient member, said member being of generally circular section and having alternate outwardly curved high parts for engagement with the interior wall of a part of a piston skirt to be expanded and inwardly curved low parts positioned out of engagement with the piston skirt, and means carried by said frame for expanding the high parts in an outward direction.

An understanding of the manner in which the above and other objects of the invention are attained may be had from the following description, reference being made to the accompanying drawings, in which:

Figure 1 is a vertical section of a wing type piston having an expander of the present invention installed therein;

Figure 2 is a horizontal section taken along the line 2—2 of Figure 1, showing the piston skirt as being appreciably smaller in diameter than the cylinder wall;

Figure 3 is a horizontal section taken along the line 2—2 of Figure 1 illustrating the expander as having been installed and the piston skirt expanded to the cylinder wall, leaving one wing member in unexpanded position;

Figure 4 is a horizontal section of a wing type piston taken along the line 4—4 of Figure 3, illustrating one thrust face of the piston skirt hav-

2

ing been expanded into contact with the cylinder wall;

Figure 5 is a detail view of the expander frame and set screw assembly in unexpanded position taken along the line 5—5 of Figure 3;

Figure 6 is a detail view of the expander frame and set screw assembly taken along the line 5—5 of Figure 3 illustrating the expander in its expanded position;

10 Figure 7 is a horizontal section of a wing type piston skirt taken along the line 7—7 of Figure 4, illustrating an alternative arrangement of the expander frame and set screw assembly;

Figure 8 is a detail view taken along the line 8—8 of Figure 7 showing the expander member in unexpanded position;

Figure 9 is a detail view taken along the line 8—8 of Figure 7 showing the expander members in expanded position;

15 Figure 10 is a bottom plan view of a wing type piston skirt incorporating a still further modification of the expander frame and set screw assembly;

Figure 11 is a bottom plan view of a conventional type piston incorporating an alternative form of expander frame and set screw assembly;

20 Figure 12 is a cross-sectional elevation of a conventional type of piston incorporating the expander frame and set screw assembly shown in Figure 11 taken along the line 12—12 of Figure 11. Like reference characters refer to like parts throughout the specification and drawings.

The numeral 20 indicates a piston such as may be employed in the cylinder 24 of an internal combustion engine. The piston is formed with a skirt 21, a head 23, and grooves 22 for receiving the conventional piston rings. The piston 20 may be of the conventional type in which the head and skirt are formed of an integral construction, and may incorporate the wing, rib and thrust plate structure constituting the subject matter of my pending application Serial No. 548,990 filed August 11, 1944, or may be of the conventional type.

25 Figures 1, 3, 4, 7 and 10 illustrate a preferred form of expander incorporated in a piston of the wing, rib and thrust plate construction. Referring to these figures, the numeral 30 indicates a thrust plate, or thrust face, against which pressure may be brought to bear to expand the wing zone area indicated by the numeral 31, i. e., the portion of the skirt which is brought into desired tolerance fit with the cylinder wall; and the non-resilient rigid rib structure is indicated by 30 the numeral 32.

A preferred form of a piston skirt expander is illustrated in Figures 3 and 4 and comprises a frame formed of a relatively rigid member 34 and a resilient member 33. These members may be formed of material such as spring steel, the member 34 being of heavier stock than the member 33. The members 33 and 34 are of generally circular section and are substantially parallel over the major portion of their length, being adapted to fit snugly between the pin bosses 37 and the piston skirt with sufficient clearance from the pin bosses that they do not come into contact with the wrist pin or the connecting rod assembly during the movement of the piston in the cylinder. The members are formed with parallel, alternate high and low points 33a, 34a, 33b and 34b respectively. The ends of the outermost resilient member 33 are turned outwardly and are adapted to fit into slots 35 formed in the piston skirt to anchor the member 33 in place. The innermost part 34, or the bridge member, is formed with upwardly turned ends 36 which fit around the edge of the pin bosses 37. The bridge member is formed with threaded housings 38 adapted to receive the screws 39 and 40. The member 33 is formed with cup shaped indentations 41 which are aligned with the housings 38 and which are adapted to receive the rounded ends of screws 39. The screws 39 act against member 33 adjacent to its ends and serve to expand that part. The screw 40 extends through resilient member 33 and acts against a pressure plate 42 which is inserted between the end of the screw and the inner wall of the piston skirt and serves to distribute the pressure to the parts of the piston skirt to be expanded. After tightening, the screws may be locked in place such as by inserting a wire or a pin through the hole 76.

Figure 2 illustrates a piston skirt as being worn to an extent such that it is of appreciably less diameter than the cylinder in which it is fitted. The manner in which the piston skirt is expanded by the expander frame is illustrated in Figures 3 and 4. Figure 5 illustrates the relative positions of the members 33 and 34 when no pressure is applied to the part 33 and Figure 6 illustrates the part 33 in expanded position by the action of the set screws 39, the set screw 40 acting directly against the thrust face through the pressure plate 42. After installation of one or more of the expander frames into the piston, as illustrated in Figures 1, 3 and 4, the set screws 39 and 40 are tightened, thereby urging the resilient member 33 and thrust face outwardly until the piston skirt has been brought into desired tolerance fit with the cylinder wall. Only one such frame may be necessary to expand a worn piston or, alternatively, more than one, as shown in Figure 3, may be employed depending upon the condition of the piston and the extent to which it may be necessary to expand it.

The expander illustrated in Figure 7 is similar in construction to the expander illustrated in Figures 1 through 4, the principal difference being in the arrangement of parts for expanding the resilient member 33.

In this modification, the parts 33 and 34 are formed with at least one and usually several spaced apart inwardly extending cone shaped indentations which form cone shaped bearing surfaces 60 between which are mounted the plates 51 and 52. These plates are similar in shape to the cone shaped bearings and are spaced apart, one at each side of the frame as illustrated in Figure 8, or may be drawn together to expand the

frame as illustrated in Figure 9, by tightening the machine screw 50 which extends through one plate and is threaded into the other.

In this modification, the resilient member 33 is expanded against the piston skirt by turning machine screws 50, which draws the plates 51 and 52 together to spread the members 33 and 34 apart and so urge the resilient member 33 against the piston skirt wing members and thrust faces.

In this modification, the expander frame is inserted into the piston and anchored in place. One or more frames may be inserted into the piston skirt, depending on the extent to which the piston is to be expanded, without interference with the reciprocal movement of the piston in the cylinder. This modification is slightly more expensive to manufacture but has the advantage that it is very easy to insert and adjust without disassembling the piston and actuating parts.

The modification of the invention illustrated in Figure 10 employs a frame of substantially circular section adapted to fit snugly into the piston skirt and formed with a resilient member 70 which is provided with alternate high and low parts 71 and 72 of dome shaped section. The high parts 71 are adapted to engage the interior wall of the piston skirt and the inwardly extending low points 72 are positioned out of engagement with the piston skirt.

A portion of the frame is formed to provide a substantially circular housing 73 which, over the width of the frame, forms a cone shaped bearing surface adapted to receive the similarly shaped plates 51 and 52. These plates are spaced apart, one at each side of the frame, as illustrated in Figure 8, and may be drawn together, as illustrated in Figure 9, by tightening the machine screw 74 which extends through one plate, 51, and is threaded into the other plate 52. In this modification only a single expander screw assembly is necessary, and expanding pressure of the frame is applied only to the piston skirt portion or portions necessary to bring all parts of the piston skirt into a desired tolerance fit within the cylinder wall. The frame is easily inserted into the piston skirt and is anchored in position such as by projections 77 formed in the side of the frame adapted to engage in the piston pin holes 75.

A further modification of the invention is illustrated in Figures 11 and 12. In this modification the resilient frame is of a roughly arch shape formed with downwardly extending sides 81 and 82. The side 81 is formed with one or more projections 83 adapted to fit into a slot 84 formed in the piston skirt. The other side 82 of the frame is formed with a drilled and threaded housing adapted to receive the set screw 85. This set screw is threaded through the frame to act against a pressure plate 86 positioned between the side of the frame and the interior wall of the skirt adjacent thereto. Expanding pressure is applied to the piston skirt by tightening the set screw 85, the pressure being equally applied to diametrically opposite portions of the piston skirt.

I have found that the piston skirt expander of the present invention has many advantages over the expanders of the prior art. While the expander is equally useful and effective when employed with a piston which as been detached from the engine and from the parts from which it is normally associated, it has the important advantage that it can be installed and employed with-

out removing the piston from the cylinder and without interfering with the wrist pin and connecting rod parts, the operation involving merely the removal of the engine crank case and the insertion of the expander into the piston.

In addition to the above advantage, the employment of the device is very simple, merely involving tightening one or more set or machine screws, either by a wrench or a screw driver, to bring the worn parts of a piston skirt into any desired tolerance fit with the cylinder wall.

In addition to the foregoing advantages, the expander is easily and cheaply manufactured, and when installed it occupies very little space in the piston skirt and does not interfere in any way with the normal reciprocal movement of the piston in its cylinder or with the wrist pin and connecting rod parts.

It will be understood, of course, that modifications may be made in the preferred embodiments of the invention described and illustrated herein without departing from the scope of the invention as defined by the appended claims.

What I claim as new and desire to protect by Letters Patent of the United States is:

1. A piston expander comprising a frame having a resilient member, said member being of generally circular section and having alternate outwardly curved high parts for engagement with the interior wall of a part of a piston skirt to be expanded, and inwardly curved low parts positioned out of engagement with the piston skirt, means for securing said frame in a piston skirt, and means carried by said frame for expanding selected high parts of said resilient member in an outward direction.

2. A piston expander comprising a frame having a resilient member of generally circular section and formed with alternate outwardly curved dome-shaped high parts for engagement with the interior wall of a part of a piston skirt to be expanded, and inwardly curved dome-shaped low parts positioned out of engagement with the piston skirt, means for securing said frame in a piston skirt, and means carried by said frame for expanding selected high parts of said resilient member in an outward direction.

3. A piston expander comprising a frame having a resilient member of generally circular section and formed with alternate outwardly curved high parts for engagement with the interior wall of a part of a piston skirt to be expanded and

inwardly curved low points positioned out of engagement with the piston skirt, at least one housing formed by said frame, and means carried by said housing for urging said high parts against the interior wall of the piston skirt.

4. A piston expander comprising a frame having a resilient member of generally circular section and formed with alternate outwardly curved high parts for engagement with the interior wall of a part of a piston skirt to be expanded and inwardly curved low points positioned out of engagement with the piston skirt, at least one housing formed by said frame, cone-shaped plates mounted in each bearing, and means for drawing said plates together to urge the high parts of said resilient member against the inner surface of the piston skirt.

5. A piston expander comprising a frame having a relatively rigid member and a resilient member, said members being of generally circular section and concentrically disposed over the major portion of their length with the resilient member outermost, said resilient member being formed with outwardly curved high parts for engagement with the interior wall of a part of a piston skirt to be expanded and inwardly curved low parts positioned out of engagement with the piston skirt, means for securing said frame in a piston skirt, and means carried by said frame for expanding the high parts of the resilient member in an outward direction.

6. A piston expander comprising a frame having a resilient member of generally circular section, means for anchoring said frame to a piston skirt, a housing carried by said frame diametrically opposite to said anchoring means, a pressure plate positioned between said housing and the piston skirt, and a set screw in said housing for acting against said pressure plate.
